UNITED STATES PATENT OFFICE

146,541

DESIGN FOR A REFRIGERATOR

Alice G. Hansen, New York, N. Y.

Application September 20, 1945, Serial No. 122,210

Term of patent 14 years

(Cl. D67—3)

To all whom it may concern:

Be it known that I, Alice G. Hansen, a citizen of the United States, residing at New York, county of New York, and State of New York, have invented a new, original, and ornamental Design for a Refrigerator, of which the following is a specification, reference being had to the accompanying drawing, forming part thereof.

The figure is a perspective view of the refrigerator showing my new design.

I claim:

The ornamental design for a refrigerator, as shown.

ALICE G. HANSEN.
